Ch. Parker Attorney

UNITED STATES PATENT OFFICE.

ROSS LEE, OF CHAFFEE, MISSOURI.

TOOL FOR INSERTING PISTON RINGS.

Application filed March 20, 1922. Serial No. 545,109.

To all whom it may concern:

Be it known that I, Ross LEE, a citizen of the United States, residing at Chaffee, in the county of Scott and State of Missouri, 5 have invented certain new and useful Improvements in Tools for Inserting Piston Rings, of which the following is a specification.

This invention relates to tools for inserting piston rings, and it comprises a pair of arms or handles pivotally connected to each other, a flexible band secured to one of said arms and adapted to be contracted by the movement of the other arm, and means for 15 adjusting the size of said band.

In the present invention, I provide a tool having a substantially circular receiving portion adapted to receive a piston ring, and means for contracting said circular portion 20 to place a piston ring within a piston ring groove and permit a cylinder to slide over the piston.

An object of the invention is the provision of a tool for inserting piston rings which 25 may be adjusted to various sizes for inserting rings on different size pistons.

A further object is the provision of a tool by means of which the piston ring may be contracted, thus eliminating the necessity of 30 fitting rings by hand.

In the accompanying drawings, I have shown one embodiment of the invention. In this showing:

Figure 1 is a side elevation of the tool in 35 use.

Figure 2 is a top plan view of the tool, showing a piston ring in position.

Figure 3 is a detail sectional view on line 3-3 of Figure 2, and,

Figure 4 is a similar view on line 4-4 of Figure 2.

Referring to the drawings, the reference numeral 1 designates a main handle which is provided with a pair of spaced lugs 2 and 3. The end of the tool is provided with an enlarged arcuate portion 4 and a band 5 of resilient metal is secured to one end of this arcuate portion. As shown, the end 6 of the band is looped about 45 a pin or bolt 7, carried by the arcuate portion of the handle. The opposite end of the arcuate portion of the handle is provided with a recess forming upper and lower guides 8. A roller 9 is supported in this recess, the roller being held in position by 50 means of a bolt 10. The band 5 is passed through this recess behind the roller and a threaded rod 11 is secured to the end of the band in any suitable manner.

An auxiliary handle 12 is pivotally mounted on the lug 3, as at 13, and this handle is provided with a heel 14 extending toward the main handle. A link formed of upper and lower plates 15 is connected to the heel of the auxiliary handle and the opposite end of the link is connected to a pivoted lever 16, formed by a pair of plates arranged above and below the handles. This lever is pivoted on the lug 2, as at 17, and is connected to a yoke or block 18, having 70 an opening 19 therein. The threaded rod passes through this opening and is retained in adjusted position by a thumb nut 20.

It will be apparent that when the auxiliary handle 12 is moved toward the main handle, as indicated in dotted lines in Figure 2 of the drawings, the threaded rod will be drawn inwardly contracting the circular portion of the band 5.

In the use of the device, a piston is removed from a cylinder for inserting new rings and the rings are arranged in the ringed grooves of the piston. These piston rings are sufficiently resilient to cause them to project beyond the walls of the piston, 85 and ordinarily in inserting piston rings, it is necessary to hold the ends of the ring in the groove by hand as the cylinder is lowered over the piston. In Figure 1 of the drawings, I have illustrated the method of 90 inserting rings. A piston 21 in which rings are to be inserted, is arranged beneath the cylinder 22, the rings 23 inserted in the grooves and the tool adjusted on the outside of the ring so that in expanded position, 95 it fits snugly around the rings. The band 5 is then contracted and is retained in this position while the cylinder block is lowered, retaining the rings in the groove until the piston moves within the cylinder when the 100 rings will be retained by the cylinder walls. It will be apparent that within certain limits of adjustment, the tool may be employed for any size piston and rings by adjusting the position of yoke 18 on the threaded 105 rod 11.

It is to be understood that the form of my invention herewith shown and described is to be taken as a preferred example of the same, and that various changes in the shape, 110 size, and arrangement of parts may be resorted to without departing from the spirit

of the invention or the scope of the subjoined claims.

Having thus described my invention, I claim:

- 5 1. In a device of the character described, a main handle, an auxiliary handle pivotally mounted thereon, a resilient ring having one end secured to said main handle, a threaded rod secured to the opposite end of said resilient ring, and connections between 10 said auxiliary handle and said rod to contract said ring when the auxiliary handle is swung on its pivot.
- 15 2. A tool for inserting piston rings comprising a main handle, an auxiliary handle pivoted thereto, a resilient ring receiving member having one end secured to the main handle, a threaded rod secured to the other end of said ring, a yoke having an opening 20 therein for the reception of said rod, and means for connecting said yoke to said auxiliary handle.
- 25 3. A tool for inserting piston rings comprising a main handle having an arcuate end, an auxiliary handle pivoted thereto, a ring receiving member secured to one side of said arcuate end, the other end of said ring

receiving member being arranged adjacent the opposite side of said arcuate end, a roller carried on the arcuate end of said main handle and forming a guide for said ring receiving member, and connections between said ring receiving member and said auxiliary handle to contract said ring receiving member when the auxiliary handle is swung on its pivot.

4. A tool for inserting piston rings comprising a main handle, an auxiliary handle pivoted thereto, a resilient ring receiving member having one end secured to the main handle, a threaded rod secured to the other end of said ring receiving member, a yoke having an opening therein for the reception of said rod, a lever pivotally mounted on said main handle and connected to said yoke, and a link connecting said lever to said auxiliary handle.

In testimony whereof I affix my signature in presence of two witnesses.

ROSS LEE.
